UNITED STATES PATENT OFFICE.

ROBERT MELVILLE BROWN, OF LONDON, ENGLAND.

CARBURETING APPARATUS FOR INTERNAL-COMBUSTION ENGINES.

1,270,486.

Specification of Letters Patent. Patented June 25, 1918.

Application filed June 13, 1917. Serial No. 174,476.

To all whom it may concern:

Be it known that I, ROBERT MELVILLE BROWN, a subject of the King of England, residing in London, England, have invented 5 certain new and useful Improvements in Carbureting Apparatus for Internal-Combustion Engines, of which the following is a specification.

This invention is for improvements in or 10 relating to carbureting-apparatus for internal-combustion engines and has for its object to provide a form of carbureter in which the atomizing of the fuel and its intermix- 15 ture with the air is more efficiently carried out than heretofore; the carbureter is suit- 20 able for use with heavy fuel, say, paraffin, or light fuel such as petrol.

According to this invention, the carbure- 25 ter has one or more fuel-feed capillary pass- ages and a corresponding number of atom- 30 izing-conduits for air-admission, so ar- ranged that their discharge-outlets are close to the discharge-outlets of the fuel-conduits but approximately at right-angles thereto 35 and thus discharge the fuel into a surround- 40 ing mixing-chamber, and is characterized by the atomizing-conduits on their intake sides having direct communication with the 45 external atmosphere by means which do not 50 communicate with the mixing-chamber at any point between the atomizing-conduits and the point at which the external atmos- 55 phere is admitted.

Preferably the mixing-chamber has a 60 closed bottom situated below the atomizing- 65 conduits to catch the heavier particles of fuel-spray and has a return duct to the fuel- 70 supply whereby such surplus fuel is carried back to the fuel-supply.

It has before been proposed to provide 75 fuel-feed capillary passages with transverse 80 passages for atomizing air, but in this ar- 85 rangement, the air which is intended to pass through the atomizing-conduits is drawn 90 from the surrounding mixing-chamber by a by-pass which extends from and returns 95 to the mixing-chamber through the said con- 100 ducts.

It has also been proposed to provide a 105 central telescopic air-admission tube with lateral perforations for admitting the air 110 from the interior of the tube into a sur- 115 rounding chamber, these radial passages being made to pierce longitudinal tapered

120 fuel-supply grooves which coöperated with 125 a surrounding plate so that the fuel would 130 be discharged into the chamber immedi- 135 ately above the plate in larger or smaller 140 quantities according to the position of the 145 tube, and therefore the capacity of that por- 150 tion of the tapered groove or grooves situ- 155 ated immediately above the plate; such 160 grooves were not arranged to operate as 165 capillary passages and in order that the 170 fuel would be discharged through them, 175 the level had to be kept near the level of 180 the said plate.

The invention involves various other fur- 185 ther details of construction, all of which are 190 hereinafter described and whereof the novel 195 features are pointed out in the claims.

In the accompanying drawings which 200 illustrate one method of carrying out this 205 invention: —

Figure 1 is a central vertical section 210 through the carbureter, and

Fig. 2 is a section of the line 2—2 of 215 Fig. 1.

The same letters indicate the same parts 220 in both figures of the drawings.

The mixing-chamber A has a well A¹ in 225 the bottom which is supplied with fuel from a surrounding float-feed chamber B con- 230 taining an annular float B¹ which operates 235 a valve (not shown) to admit fuel by a con- 240 duct B². The float and its mechanism for 245 operating a valve constitute no part of the 250 present invention and need not therefore 255 be further described.

The bottom of the mixing-chamber A 260 should be perforated at one point to equalize 265 the pressure in the chambers A and B so 270 that there may be no tendency to draw the 275 fuel up from the well A¹ into the mixing- 280 chamber except through the capillary pas- 285 sages. Provided the pressure is equalized 290 between these two chambers, there is no 295 tendency for the fuel to rise in the well 300 through any reduction of pressure in the 305 chamber A, as the float keeps the valve 310 controlling the supply-conduit B² closed ex- 315 cept when the level in the chamber B falls 320 below a predetermined limit.

Fixed in the center of the well is a tube 325 C which serves as a support for a second 330 tube D. The tube D has an exterior flange 335 D¹ at the top and exterior grooves D² which 340 extend from the bottom of the tube approxi- 345

2
mately to the said flange. Near the under-side of the flange is a series of perforations D³, one for each groove, the throughway of the perforations being set at right-angles 5 to the direction of the grooves and radial to the tube D each air-tube being further centrally alined with its coöperating fuel groove. The bottom of the tube D is open to the atmosphere through its supporting tube C, which extends right through the 10 bottom of the well A¹ but the top of the tube D has seated on it a valve E. This valve has a spindle E¹ which extends down through the tube and through a bridge piece E² which projects downward from the bottom of the well A¹. The bottom of the spindle is thus kept in position by the bridge-piece and the top is centralized by a 15 gauze diaphragm H secured within the mixing-chamber A. The valve E is free to slide on its spindle E¹ and is kept down upon the top of the tube D by a spring E³ which bears at one end against the valve and at the other end against a collar E⁴ on 20 the spindle E¹. At the bottom end of the spindle E¹ where it projects beyond the cap E², adjusting nuts E⁵ are provided so that the pressure of the spring on the valve can be regulated by screwing the nuts farther 25 along the spindle or withdrawing them farther toward the end of the same. The diaphragm H yields sufficiently to permit of this adjustment or the spindle could be made to slide through it.

30 35 A third tube F is telescoped on to the tube D and is a close fit thereon. This tube does not come down quite to the bottom of the tube D, so that the grooves D² at the bottom are left exposed to the fuel 40 in the well A¹. The upper end of the tube F has a flange F¹ similar to the flange D¹ on the tube D and perforations F² are provided in this flange which register with the perforations D³ in the tube D. The 45 tube F may be held friction-tight in its proper position on the tube D, that is, with its perforations F² in register with the perforations D³, or it may be fixed to the tube by a screw or other means.

50 55 Projecting upward from that part of the bottom of the mixing-chamber A which surrounds the well A¹, is a series of upright tubes G whose upper ends are situated above the level of the perforations D³, F², in the tubes D and F, and whose lower ends extend down through the float-feed chamber B and communicate with the atmosphere through the bottom of the said float-feed chamber. A plate G¹ controlled by a Bowden wire 60 (not shown) connected to a finger G² and having in it perforations G³ which register with the tubes G, can be moved to partially or wholly close the lower ends of the tubes if desired.

65 65 At the top of the mixing-chamber are two

further gauze diaphragms H¹. These are shown as mounted on certain parts which are detachable from the mixing-chamber, but they may be mounted elsewhere and may be increased in number if desired.

Above the gauze diaphragms is a throttle-valve of known type comprising a spherical casing J in the center of which is mounted a cylindrical guide-member J¹. The guide-member is closed at the top but is open at 70 the bottom and is provided with a series of ports J², which, when open, throw the bore of the guide-member into communication with the chamber formed between the guide-member and the spherical casing J. Within the guide-member operates a piston J³ which is controlled by a Bowden-wire J⁴. Communicating with the chamber formed within the spherical casing J is a conduit K which constitutes the induction-conduit of the engine, and the throttle-valve so far described is a known device. For the purpose of the present invention, however, an auxiliary air-opening is provided at J⁵ whereby air can be admitted from the atmosphere direct to the interior of the spherical casing J and thence to the induction-conduit. This air-opening is controlled by a register-plate J⁶ which can be adjusted to any desired position on a fixed plate J⁷ which is secured over the air-admission orifice. The plate J⁶ may be provided with operating means whereby it can be controlled during driving.

The operation of this carbureter is as follows:—

When running, the piston J³ of the throttle-valve J is pulled back by the Bowden-wire J⁴ a sufficient distance to open more or less of the ports J² so that the engine can 105 thus draw mixture from the chamber A through the induction-conduit K. The register-plate J⁶ is kept in the closed position when the engine is working and only opened 110 for scavenging purposes or to cool the engine by admitting pure air to the engine when the vehicle is running free.

The fuel always remains at the level of the perforations D³ because the grooves D² are sufficiently fine to draw it up to this point by capillary attraction and it is discharged thence by the rush of air through the perforations D³. It will be noted that the direction of discharge of the air is at right-angles to that of the discharge of the fuel, and as the fuel will be delivered in fine jets owing to the smallness of the bore of the conduits D², it will be thoroughly atomized by the action of the air blowing through the perforations D³, which may be termed the atomizing-conduits. The fuel is, of course, driven out toward the walls of the mixing-chamber by the atomizing air and is thus spread out radially from the tube D in a plane approximately at right-angles to the 115 120 125 130

direction of suction of the engine, and which plane is at a lower level than the upper ends of the air-tubes G. The heavier portions of fuel thus strike the wall of the chamber A and being deposited thereon run back to the well A¹ so that only the finely atomized fuel is carried forward with the extra air which enters the mixing-chamber by the valve E and tubes G. The admission of air by the valve E is effected by the suction of the engine which causes the valve to be lifted against the action of its spring E³. The degree of lift permitted this valve is regulated by the driver by operating the nuts E⁵ according to the working conditions of the day. The air admitted by the tubes G is regulated by the plate G¹ which is operated by the driver as desired.

The gauze diaphragms H, H¹ further eliminate any heavy particles of fuel, so that only a mixture of thoroughly atomized particles is delivered through the throttle J to the engine.

The carbureter A is conveniently heated, and for this purpose is surrounded by a jacket L so that a portion of the exhaust gases or other heating fluid may be passed around it.

Obviously the grooves D² can be formed in the inner face of the outer tube F if desired, or partly in the outer tube and partly in the tube D².

The object of setting the upper ends of the air-tubes G at a level which is above that of the discharge from the atomizing conduits D³, is to prevent the air entering by these tubes from carrying forward the heavier particles of fuel. The lighter particles will rise and be caught by this incoming air, while the heavier will either strike the wall A, as already stated, or will fall direct to the bottom and thus return to the well A¹. It will be appreciated that it might not be essential in all cases to admit the air by the tubes G above the level of the fuel-discharge, but they should be so placed that the air entering by them does not catch up the larger atoms or particles of fuel but only carries the finely atomized fuel forward to the engine. If the walls A are heated, some of the fuel which strikes them will be vaporized and will thus pass on with the finely divided fuel.

It will be appreciated that what has been described throughout this specification as a plurality of fuel-jets and atomizing-conduits, could, in fact, take the form of a single annular fuel-conduit and a corresponding single annular atomizing-conduit as will be readily understood.

By placing the atomizing-conduits D³ at approximately the height shown in the drawing above the closed bottom of the mixing-chamber constituted by the well A¹ and its upper outward extension, the fuel is pre-

vented from striking the bottom of the chamber, which would produce undue condensation. The spray comes from the conduits D³ in a fan-shape and when the proportions are approximately those shown in the drawing, the lowest portion of this fan is clear of the said bottom of the mixing-chamber.

The valve E is not essential to the apparatus and could be dispensed with, the tube D being then closed at the top so that all the air passing through it has to escape by the atomizing-conduits D³. All that is necessary is that the end of the tube D shall be closed or partially closed so as to offer resistance to the incoming air and thus compel a considerable portion of the air to pass through the conduits D³. If the engine end of the tube D is closed then the resistance of course is absolute, but with the spring-controlled valve E shown, the degree of resistance can be varied by adjusting the tension of the spring E³ by means of the nuts E⁵.

What I claim as my invention and desire to secure by Letters Patent is:—

1. In a carbureter, the combination of, a mixing-chamber, a fuel-container, an air-admission tube (D) which extends into the mixing-chamber at one end and at the other end is in free communication with the atmosphere, fuel-feed capillary conduits set around the said tube and extending from the fuel-container up the same with their discharging mouths in the direction of the engine-suction, the tube being provided with radial passages situated one at the top of each fuel-feed conduit which radial passages communicate between the interior of the tube and the mixing-chamber, and means at the inner end of the tube beyond the said radial passages to offer resistance to the air drawn in from the outer end of the tube, for the purpose set forth.

2. In a carbureter, the combination of, a mixing-chamber, a fuel-container, an air-admission tube (D) which extends into the mixing-chamber at one end and at the other end is in free communication with the atmosphere, fuel-feed capillary conduits set around the said tube and extending from the fuel-container up the same with their discharging-mouths in the direction of the engine-suction, the tube being provided with radial passages situated one at the top of each fuel-feed conduit which radial passages communicate between the interior of the tube and the mixing-chamber, and a suction-valve (E) which opens in the direction of the engine-suction and is yieldingly-controlled to close the inner end of the tube at a point beyond the radial air-passages, for the purpose set forth.

3. In a carbureter, the combination of, a mixing-chamber, a fuel-container, an air-admission tube (D) which extends into the

mixing-chamber at one end and at the other end is in free communication with the atmosphere, fuel-feed capillary conduits set around the said tube and extending from the fuel-container up the same with their discharging-mouths in the direction of the engine-suction, the tube being provided with radial passages situated one at the top of each fuel-feed conduit which radial passages communicate between the interior of the tube and the mixing-chamber, and a suction valve (E) which opens in the direction of the engine-suction and is yieldingly-controlled to close the inner end of the tube at a point beyond the radial air-passages, the stem of which valve is free relatively to the valve but carries an abutment for a spring above the valve, which spring is in compression between the valve and the said abutment, the said stem being carried down through the bottom of the carbureter where it is provided with adjusting nuts (E⁵) for ready adjustment of the pressure of the spring, for the purpose set forth.

4. In a carbureter, the combination of, a mixing-chamber, an air-admission tube (D) which extends into the mixing-chamber at one end and at the other end is in free communication with the atmosphere, a fuel-container surrounding the base of the tube but through the bottom of which the tube has communication with the external atmosphere, a close-fitting sleeve (F) on the tube, longitudinal capillary passages formed in one of the contacting surfaces of the sleeve and tube which passages at the bottom have communication with the fuel-container and at the top do not extend so far as the top of the tube but are met by transverse radial passages which extend through both the tube and the sleeve, one such radial passage being allotted to each longitudinal passage, and means at the inner end of the tube beyond the said radial passages to offer resistance to the air drawn in from the outer end of the tube, for the purpose set forth.

5. In a carbureter, the combination of, a mixing-chamber, an air-admission tube (D) which extends into the mixing-chamber at one end and at the other end is in free communication with the atmosphere, a fuel-container surrounding the base of the tube but through the bottom of which the tube has communication with the external atmosphere, a close-fitting sleeve (F) on the tube, longitudinal capillary passages formed in one of the contacting surfaces of the sleeve and tube which passages at the bottom have communication with the fuel-container and at the top do not extend so far as the top of the tube but are met by transverse radial passages which extend through both the tube and the sleeve, one such radial passage being allotted to each longitudinal passage, and a suction valve (E) which opens in the

direction of the engine-suction and is yieldingly-controlled to close the inner end of the tube at a point beyond the radial air-passages, for the purpose set forth.

6. In a carbureter, the combination of, a mixing-chamber having a bottom for collecting the heavier particles of fuel-spray, the said bottom being so constructed as to prevent these from passing by gravity out to the external atmosphere and having return draining means to the fuel-container, a fuel-feed capillary conduit extending from the fuel-container to a point in the mixing-chamber which is above the bottom of the said chamber and has its mouth directed to discharge in the direction of the engine-suction; an atomizing-conduit having its discharge-outlet close to the discharge-outlet of the fuel-conduit but approximately at right-angles thereto to discharge the fuel laterally outward into the surrounding mixing-chamber in the form of a spreading jet and having its other end in direct communication with the external atmosphere without communicating with the mixing-chamber at any point between the discharge end of the atomizing-conduit and that at which the external atmosphere is admitted to the atomizing-conduit, the height of the discharge end of the fuel-feed conduit from the bottom of the mixing-chamber being such as to insure that the said spreading jet shall not impinge against this bottom, and means for admitting air to the mixing-chamber under the action of the engine-suction, the air-admission points being so placed that the incoming air does not come into the path of the heavier particles of fuel which fall to the draining bottom of the mixing-chamber, for the purpose set forth.

7. In a carbureter, the combination of, a mixing-chamber having a bottom for collecting the heavier particles of fuel-spray, the said bottom being so constructed as to prevent these from passing by gravity out to the external atmosphere and having return draining means to the fuel-container, a fuel-feed capillary-conduit extending from the fuel-container to a point in the mixing-chamber which is above the bottom of the said chamber and has its mouth directed to discharge in the direction of the engine-suction, an atomizing-conduit having its discharge outlet close to the discharge-outlet of the fuel-conduit but approximately at right-angles thereto to discharge the fuel laterally outward into the surrounding mixing-chamber in the form of a spreading jet and having its other end in direct communication with the external atmosphere without communicating with the mixing-chamber at any point between the discharge end of the atomizing-conduit and that at which the external atmosphere is admitted to the atomizing-conduit, the height of the dis-

charge end of the fuel-feed conduit from the bottom of the mixing-chamber being such as to insure that the said spreading jet shall not impinge against this bottom, and 5 air-admission tubes (G) projecting from the bottom of the mixing-chamber and extending to a point above the level of the discharge of atomized fuel, for the purpose set forth.

10 8. In a carbureter, the combination of, a mixing-chamber having a central well and a bottom which slopes from the outer walls to the top of the well, a fuel-container beneath the said bottom and surrounding the 15 well but having communication therewith, an air-admission tube (D) situated within the well and which extends up therefrom into the mixing-chamber and has free communication through the bottom of the well 20 with the atmosphere, fuel-feed capillary conduits set around the said tube and extending from the well with which they have free communication at their lower ends up to points on the tube which lie within the 25 mixing-chamber at which points the tube is provided with radial passages one allotted to each capillary conduit, and means at the inner end of the tube beyond the said radial passages to offer resistance to the air drawn

in from the outer end of the tube, for the 30 purpose set forth.

9. In a carbureter, the combination of, a mixing-chamber having a central well and a bottom which slopes from the outer walls to the top of the well, a fuel-container beneath the said bottom and surrounding the well but having communication therewith, an admission-tube (D) situated within the well and which extends up therefrom into the mixing-chamber and has free communication through the bottom of the well with the atmosphere, a close-fitting sleeve (E) on the said tube, longitudinal capillary passages formed in one of the contacting-surfaces of the sleeve and tube which passages at the bottom have communication with the well in which the tube is situated and at the top are met by transverse radial passages which extend through both the tube and the sleeve, one such radial passage being allotted to each longitudinal passage, and means at the inner end of the tube beyond the said radial passages to offer resistance to the air drawn in from the outer end of the tube, for the purpose set forth. 55

In testimony whereof I have signed my name to this specification.

ROBERT MELVILLE BROWN.
